UNITED STATES PATENT OFFICE.

JAMES H. TAYLOR, OF WESTFIELD, MASSACHUSETTS.

CHURN.

SPECIFICATION forming part of Letters Patent No. 308,215, dated November 18, 1884.

Application filed April 30, 1884. (No model.)

To all whom it may concern:

Be it known that I, JAMES H. TAYLOR, a citizen of the United States, residing at Westfield, in the county of Hampden and State of Massachusetts, have invented certain new and useful Improvements in Churn Barrels or Cylinders; and I do hereby declare that the following is a full, clear, and exact description thereof, reference being had to the accompanying drawings, and to the letters of reference thereon, in which—

Figure 1 is an end elevation of my improved churn-barrel. Fig. 2 is a longitudinal central section of the same. Fig. 3 is a plan view of the fastening devices for drawing the band tight, and Fig. 4 is a longitudinal central section of the same.

The invention consists in the construction and arrangement of parts, as will be herein-after fully described and claimed.

A represents the churn-barrel, composed of a series of staves, ends A', and cover C. The ends A' have the usual bearings or sockets in their centers, and are rabbeted, as shown in Fig. 2, to form a seat for the cover to rest on. The cover is provided with handles D, ventilators F F', and glass E, all of the usual construction. To the upper part of the heads A', opposite the rabbets therein, are secured plates G, having handle-sockets G' formed thereon. To the ends of the plates G metal straps a are secured or formed. These straps are formed or provided with pins b on the outer sides of their ends, as shown clearly in Fig. 4. A rectangular frame, g, is formed with a cross-piece, g', to which is pivotally secured a button or disk, d, that has eccentric grooves c in its under surface on opposite sides of the pivots. The ends of the bands a pass through the end bars of the frame, which are slotted for this purpose, and the pins b are brought into engagement with the slots c.

By turning the disk d by means of the finger-lugs h the bands will be tightened or loosened, according to the direction in which said disk is turned.

The barrel or cylinder is put together by placing the staves on the heads beneath the bands a, and then turning the button d to cause the bands to firmly bind the said staves to the heads.

Having now described my invention, what I claim as new, and desire to secure by Letters Patent, is—

1. The bands a, provided with pins b on their free ends, in combination with the frame g, through the end bars of which the bands pass, and the button d, pivoted to the frame, and having eccentric grooves c c, engaging the pins b, substantially as set forth.

2. The plate G, having the handle-socket G' and the bands a formed therewith, and the pins b on the free end of said bands, in combination with the frame g and the pivoted button d, formed with eccentric grooves engaging the pins b, substantially as set forth.

3. The combination, with the churn-cylinder A, composed of staves, of the heads A', plates G, secured to said heads, the bands a, secured to the plates, and provided with pins b on their free ends, frames g, through the end bars of which the bands a pass, and the buttons d, pivoted to the frames, and formed with eccentric grooves c, engaging the pins b, substantially as set forth.

4. The combination, with the cylinder A, of the bands a, having pins b on their ends, the frames g, and the pivoted disks d, having eccentric slots c and finger-lugs h, substantially as set forth.

JAMES H. TAYLOR.
